INCANDESCENT ELECTRIC LAMP

John W. Marden, East Orange, and George Meister, Newark, N. J., assignors to Westinghouse Electric & Manufacturing Company, East Pittsburgh, Pa., a corporation of Pennsylvania

Application November 13, 1936, Serial No. 110,584

13 Claims. (Cl. 176—16)

This invention relates to incandescent electric lamps and more particularly to one having a coiled filament normally operating in an atmosphere consisting principally of mercury vapor.

Many years ago mercury was proposed as a gas filling for lamps. Attempts to use it failed because when such a lamp was used on constant voltage the filament had to be excessively heated while the mercury was being vaporized to produce the required pressure for protecting the filament.

After moisture is eliminated from a lamp bulb so that the enclosed filament is not destroyed by chemical action, the life of the filament is dependent on the rate of evaporation therefrom. Gases suppress evaporation, but also tend to cool the filament. In lamps having filaments of the larger sizes, especially coils, the gain in light by reason of the higher temperatures which can be used in an inert gas, such as nitrogen, for example, exceed the losses due to cooling, and the gas-filled lamp is more efficient than that of the vacuum type. Mercury vapor is more desirable as a filling than nitrogen, due to the poorer heat conductivity of this metal vapor.

With the foregoing consideration in mind, it is an object of our invention to produce an electric lamp comprising an incandescent filament operating in an atmosphere consisting mainly of mercury vapor.

Another object of our invention is the provision of an incandescent electric lamp of the gas type, in which the gas filling is normally substantially replaced by mercury vapor.

A further object of our invention is the provision of an electric lamp comprising an envelope enclosing a filament surrounded by inert gas and containing mercury, so that when the filament is operated at incandescence, the gas filling will protect it from excessive vaporization until the mercury is vaporized sufficiently to accomplish that purpose.

A still further object of our invention is to provide an electric lamp in which a coiled filament initially operates in an atmosphere of inert gas until mercury, included in the bulb, is sufficiently vaporized to such a pressure that its effect substantially replaces that of said gas as a protective medium against excessive vaporization of the filament, and allow said filament to operate at an efficiency higher than usual, because it is surrounded by a medium of heat conductivity poorer than the usual surrounding medium.

An additional object of our invention is the provision of a novel method of making an incandescent electric lamp, including the introduction of a measured quantity of mercury into the bulb thereof, said mercury being a small amount so measured that it is completely vaporized during normal lamp operation.

Other objects and advantages of the invention relating to the particular arrangement and construction of various parts will become apparent as the description proceeds.

Referring to the drawing illustrating our invention, the scope whereof is defined by the appended claims:

15 Fig. 1 is a vertical sectional view of a lamp embodying our invention, portions thereof being illustrated in elevation;

Fig. 2 is a transverse sectional view on the line II—II of Fig. 1, in the direction of the arrows, 20 portions being illustrated in elevation and parts broken away;

Fig. 3 is a vertical sectional view, with parts in elevation, of another embodiment of our invention;

25 Fig. 4 is an elevational view of a further embodiment of our invention;

Fig. 5 is an elevational view of a still further embodiment of our invention;

30 Fig. 6 is a diagrammatic view showing the characteristics of a choke coil which may be employed with the embodiment of Fig. 5;

Fig. 7 is an elevational view illustrating apparatus which may be employed in introducing a small measured quantity of mercury into a lamp 35 bulb; and

Fig. 8 is a fragmentary view of a modified form of apparatus, such as shown in Fig. 7.

Referring to the drawing in detail, like parts being designated by like reference characters, 40 and first considering the embodiment of our invention illustrated in Figs. 1 and 2, there is shown a lamp 10 comprising a relatively small mercury-enclosing hard glass bulb 11, allowing for operation at a temperature high enough to 45 keep a small quantity of mercury 19 completely vaporized, having a press 12, through which leads 13 and 14 extend and are connected to a concentrated or coiled filament 15. Said filament is preferably formed of tungsten and positioned 50 near, but below, the center of the bulb, so that the latter is heated as uniformly as possible. The filament, of the present embodiment, is so mounted that it takes the form of a W in elevation, as shown in Fig. 1, being curved in plan, as shown 55 most clearly in Fig. 2. In order to hold the fila-

ment in the shape illustrated, supporting members 16 and 17, and 18 extend from the press 12, and are secured to intermediate portions of said filament, as illustrated. The press 12 is desirably of the "inverted," "external," or "non-re-entrant" type illustrated, so as to avoid cold pockets in which some of the mercury would condense.

Disposed in the bulb 11 is a small quantity of mercury 19, desirably measured so that all will be vaporized during normal operation of the lamp, to produce an operating pressure of from one-half to about one atmosphere. By using a small, completely vaporizable amount of mercury, rather than a surplus, excessive mercury pressure, short circuiting of the coils by droplets, and interference with the transmission of light through the bulb by condensed vapor, are avoided, as superheating occurs after complete vaporization. The exact amount of mercury used in a given lamp will, of course, depend on the volume of the envelope and the normal or usual running or operating lamp temperature. It may be introduced into the bulb, during the operation of manufacturing the lamp, in any one of various ways, a preferred apparatus for the purpose being illustrated in Fig. 7. Employing this apparatus, the lamp bulb 11 is connected by means of a capillary tube 20 to a two-way mercury seal stop cock 21, having extending therefrom a capillary tube 22 connecting with a vessel 23 containing mercury 24.

The vessel 23 is likewise connected to a two-way stop cock 25 by means of a tube 26 so that it may be alternatively connected to a vacuum pump by means of a tube 27, or to the atmosphere by means of a tube or air inlet 28. The stop cock 21 has a tube 29 comprising a capillary portion graduated, as indicated at 30, and connected to the vacuum pump, like the tube 27.

The bulb 11 has the leads 13 and 14, sealed in as free from oxide as possible, it being pointed out that impure gas, moisture, badly oxidized leads, and oxidized filaments result in discolored lamps. The lamp is baked and gas-filled in the regular manner. In this case the gas may be introduced into the bulb at the proper time by means of a gas inlet, not shown, connecting with the tube 29, so that when the lamp is first operated, and before the mercury is substantially vaporized, there will be a protective atmosphere surrounding the filament.

When it is desired to introduce the mercury, the stop cock 21 is turned to the position illustrated in Fig. 7, and the stop cock 25 slowly opened to allow air to enter and force the mercury up until it reaches the height indicated by X, which represents the desired measured quantity of mercury to be inserted in the bulb. The connection of the tube 29 with the vacuum pump causes the mercury to rise to the indicated level. The desired level can be accurately controlled by manipulating the stop cock 25, as it will be appreciated that turning the stop cock handle, so that the tube 26 is connected to the vacuum pump, results in lowering the mercury in the tubes 22 and 29, and turning it to connect with the air inlet 28 results in raising the mercury in said tubes.

After the desired length X of mercury has been measured in the graduated portion 30 of tube 29, the stop cock 21 is turned so as to allow the measured quantity of mercury to flow from the tube 29 through the stop cock and tube 20 into the bulb 11 of the lamp 10, before or during

the time the gas filling is introduced. A preferred gas filling consists of a mixture of 86% argon and 14% nitrogen, by volume, at a pressure of about 150 millimeters of mercury. Other fillings inert to the tungsten filament, and having similar heat dissipating properties, may be satisfactorily employed; for example, a mixture of 77% helium and 23% nitrogen, by volume, at a pressure of about 65 millimeters of mercury.

Fig. 8 illustrates an alternative embodiment of the apparatus illustrated in Fig. 7, in which a bypass tube 31 with a stop cock 32 serves to directly connect the tube 29^a with the tube 20^a, thereby facilitating the exhausting operation by making it unnecessary for the gas in the bulb 11 to pass through the capillary portions of the tubes 29^a and 20^a, and the stop cock 21^a.

Alternative means of introducing mercury include placing small tubes of mercury in the bulb exhaust tube, which tubes are broken after removing from the pump and the mercury run or distilled into the bulb. Also, mercury may be distilled from a side tube into the bulb, or applied to the filament like a getter as a decomposable mercury compound. However, we prefer the introduction of the mercury as described in connection with Fig. 7 or Fig. 8.

Alternative forms of lamps are illustrated in Figs. 3, 4, and 5. In Fig. 3, a lamp 10^a is illustrated having a generally cylindrical bulb 11^a with a pair of presses 12^a. At one end a press 12^a receives the lead 13^a and at the other another press receives the lead 14^a, to which leads are connected the normally vertical coiled-coil filament 15^a.

Fig. 4 illustrates an embodiment of our invention similar to Fig. 3, except that the bulb 11^b is generally frusto-conical with the small end down, rather than cylindrical as in Fig. 3, but, like the embodiment of that figure, also preferably contains a coiled-coil filament designated by the reference character 15^b. In the forms of both Figs. 3 and 4, a measured quantity of mercury is included, as designated by the reference character 19^a in Fig. 3, and a filling of gas such as described in connection with Figs. 1 and 2. The advantage of the inverted generally-conical form of bulb, illustrated in Fig. 4, is that the temperature is maintained at greater uniformity, as the bulb wall in the hotter portion thereof is farther from the filament. In both of these forms, the presses are desirably covered with a fireproof insulating material, such as asbestos, designated by the reference character 33, in Fig. 3 and 33^b in Fig. 4.

Referring now to the embodiment of our invention illustrated in Fig. 5, we have a lamp 10^c comprising an envelope 11^c and enclosing a preferably coiled or concentrated filament 15^c, connected with lead wires 13^c and 14^c extending through a press 12^c, and disposed in a fairly high vacuum, for example, such as in an inert gas, argon, or neon, at a pressure substantially lower than that of the preceding embodiments, such as for example as that of from about ten to fifty millimeters of mercury. A measured quantity of mercury 19^c is enclosed in the bulb, as in the previous embodiments.

The lamp of Fig. 5 is provided with arcing points 34 and 35 and designed for use with a choke coil or other device having the characteristics illustrated in Fig. 6, in order to protect the filament until the mercury vapor pressure builds up sufficiently for that purpose.

When the lamp is first turned on, an arc

breaks between the points 34 and 35 and the lamp runs at low voltage, for example, 20 volts, as indicated in the diagram in Fig. 6, until the mercury heats. The mercury pressure will increase until the voltage impressed on the lamp rises to 80 to 90 volts, when the arc is extinguished and the full load is then thrown on the filament 15. When the lamp is normally operating at say two amperes, as represented in Fig. 6, it will burn at 105 to 110 volts, where the line voltage is 115, so that the power factor is then at least 90%.

In all the forms of our invention illustrated it is necessary to operate the lamp hot in order to maintain the required mercury vapor pressure, which should be from one-half to about one atmosphere in order to suppress the vaporization of the tungsten to the desired extent. In order, therefore, to protect the bulb from air currents, fixtures from overheating, and the user from burns, the lamps of all of our embodiments are desirably used with a housing 36 as shown in Figs. 1 and 2, and asbestos coverings on the presses, as illustrated in Figs. 3 and 4.

The housing 36 may comprise a glass envelope 37 receiving the lamp and protected by a disc 38, of mica or the like, through which the leads 13 and 14 pass for connection with a special base 39. The base 39 may have a threaded outer metal shell 40 forming one contact and separated from a central contact 41 by a glass or other insulative filling 42, from which an enlarged portion 43 of the base extends into embracing relationship with the peripheral portion of the open end of the glass enclosing member 37, being desirably sealed thereto by cement or the like, as indicated at 44. The upper portion of each bulb may be provided with a metallic shield or reflecting surface of gold, platinum, or the like, instead of asbestos to conserve and distribute the heat and use the light to the best advantage, as indicated at 45.

From the foregoing, it will be seen that we have devised an incandescent lamp, in which the filament normally operates in an atmosphere consisting principally of completely vaporized mercury, or superheated mercury vapor, which has a relatively low heat conductivity, compared with the inert gas usually employed as a filling, thereby making it possible to operate at higher efficiency, or with smaller heat losses under comparable conditions.

Although preferred embodiments of our invention have been disclosed, it will be understood that modifications may be made within the spirit and scope of the appended claims.

We claim:

1. An electric lamp comprising a sealed glass envelope containing a tungsten filament, an inert gaseous filling and mercury, a transparent outer casing enclosing said envelope, a base on said casing, lead-in conductors extending from said base to said filament, and a disc through which said lead-in conductors extend, disposed in said outer casing, and spaced from said base, in order to protect it from over-heating during operation of said lamp.

2. The method of introducing a desired quantity of mercury into an electric lamp comprising connecting a reservoir of mercury through a two-way valve to said lamp and a vacuum pump, allowing said mercury to be drawn to a calibrated portion of a tube between said valve and pump, until a measured quantity is trapped by said valve, and turning said valve until said quantity

is connected to the lamp and allowed to flow thereto.

3. An electric lamp comprising an envelope, an incandescent filament disposed therein and supported from leads, and arcing points extending from said leads into close proximity to one another, said envelope containing mercury which during operation is adapted to form the main atmosphere surrounding the filament, a transparent outer casing enclosing said envelope, a base on said casing, lead-in conductors extending from said base to said filament, and a disc through which said lead-in conductors extend, disposed in said outer casing and spaced from said base, in order to protect it from over-heating during operation of said lamp.

4. An electric lamp comprising a sealed glass envelope, an incandescent tungsten filament, less than $\frac{1}{2}$ of an atmosphere of an inert gas filling, mercury in said envelope and so small in quantity as compared with the volume of and usual running temperature in the envelope that it is completely vaporized during normal operation of the lamp to produce a substantial protective mercury vapor pressure greater than that of said gas, a transparent outer casing enclosing said envelope, a base on said casing, lead-in conductors extending from said base to said filament, and a disc through which said lead-in conductors extend disposed in said outer casing and spaced from said base in order to protect it from over-heating during operation of said lamp.

5. An electric lamp comprising a sealed envelope containing an incandescent filament and less than one-fifth of an atmosphere of an inert gas filling, mercury in said envelope and so small in quantity, as compared with the volume of and normal running temperature in the envelope, that it is completely vaporized to produce an operating pressure of from one-half to about one atmosphere during normal operation of the lamp, a transparent outer casing enclosing said envelope, a base on said casing, lead-in conductors extending from said base to said filament, and a disc through which said lead-in conductors extend, disposed in said outer casing and spaced from said base, in order to protect it from over-heating during operation of said lamp.

6. An electric lamp comprising a sealed envelope containing a tungsten filament, an inert gaseous filling, and mercury so small in quantity, as compared with the volume of and usual running temperature in the envelope, that it is completely vaporized during normal operation of the lamp to produce a substantial protective mercury vapor pressure, said envelope being substantially frusto-conical, the filament disposed substantially co-axial therewith, and said lamp being adapted for operation with the large end uppermost, in order to insure more nearly uniform temperature conditions in the envelope, a transparent outer casing enclosing said envelope, a base on said casing and disposed adjacent the large end of said envelope, lead-in conductors extending from said base to said filament, and a disc through which said lead-in conductors extend, disposed in said outer casing and spaced from said base, in order to protect it from over-heating during operation of said lamp.

7. An electric lamp comprising a sealed envelope containing a tungsten filament, an inert gaseous filling at a pressure of about one hundred and fifty millimeters, a measured amount of mercury in said envelope and so small in quantity, as compared with the volume of and usual run-

ning temperature in the envelope, that it is completely vaporized during normal operation of the lamp to produce a pressure of more than one half an atmosphere, a transparent outer casing enclosing said envelope, a base on said casing, lead-in conductors extending from said base to said filament, and a disc through which said lead-in conductors extend, disposed in said outer casing and spaced from said base, in order to protect it from overheating during operation of said lamp.

8. An electric lamp comprising a sealed envelope, a tungsten filament mounted therein, a gaseous filling consisting of about eighty-six percent argon and about fourteen percent nitrogen and at a pressure of about one hundred and fifty millimeters of mercury, mercury in said envelope and so small in quantity that it is completely vaporized during normal operation of the lamp to produce an operating pressure of from one-half to one atmosphere, a transparent outer casing enclosing said envelope, a base on said casing, lead-in conductors extending from said base to said filament, and a disc through which said lead-in conductors extend, disposed in said outer casing and spaced from said base, in order to protect it from over-heating during operation of said lamp.

9. An electric lamp comprising a sealed envelope, a tungsten filament mounted therein, a gaseous filling consisting of about seventy-seven percent helium and about twenty-three percent nitrogen and at a pressure of about sixty-five millimeters of mercury, mercury in said envelope and so small in quantity that it is completely vaporized during normal operation of the lamp to produce an operating pressure of from one-half to one atmosphere, a transparent outer casing enclosing said envelope, a base on said casing, lead-in conductors extending from said base to said filament, and a disc through which said lead-in conductors extend, disposed in said outer casing and spaced from said base, in order to protect it from over-heating during operation of said lamp.

10. An incandescent electric lamp comprising a translucent envelope of high melting point vitreous material having a filament mounted therein and containing a quantity of mercury and a filling of an inert gas, the amount of mercury being such that at the operating temperature of the lamp it is completely vaporized and the pressure of the mercury vapor lies between one-half and one atmosphere, a transparent outer casing enclosing said envelope, a base on said casing, lead-in conductors extending from said base to said filament, and a disc through which said lead-in conductors extend, disposed in said outer casing and spaced from said base, in order to protect it from over-heating during operation of said lamp.

11. An incandescent filament electric lamp with an auxiliary discharge starting device comprising an enclosing envelope, leads and an incandescent filament supported therefrom and disposed therein, arcing points extending from

5 said leads into close proximity to one another, inert gas at low pressure in said envelope and surrounding said leads and points, a quantity of mercury in said envelope, and means for applying such electrical power to said leads and so conserving the heat developed in the envelope that first an arc breaks between said points and the lamp runs at reduced voltage with little heat in the filament, then the mercury in the envelope is vaporized by the heat from the arc, builds up a relatively high pressure of mercury vapor and quenches the arc, causing the full voltage to be impressed on the filament, and then the filament operates at desired incandescence in the heat-developed atmosphere consisting mainly of mercury vapor.

10 12. An incandescent filament electric lamp with an auxiliary discharge starting device comprising an enclosing envelope, leads and an incandescent filament supported therefrom and disposed therein, arcing points extending from said leads into close proximity to one another, inert gas as a pressure of from about ten to fifty millimeters of mercury in said envelope and surrounding said leads and points, a quantity of mercury disposed in said envelope and measured so that it is completely vaporized during lamp operation, a ballast device connected in series with said lead-in conductors, and power means 20 for so operating said lamp through said ballast that first an arc breaks between said points, because of the initial low pressure of the surrounding gas, and the lamp runs on a relatively high current at reduced voltage, the heat of said arc then vaporizes the mercury building up the pressure thereof so high that said arc is extinguished, whereupon said filament then operates on full voltage at the desired temperature in the heat-developed and maintained protective atmosphere consisting mainly of mercury vapor.

25 13. The method of operating an incandescent filament electric lamp having an auxiliary discharge starting device; which lamp comprises an enclosing envelope containing mercury and having leads, an incandescent filament supported from said leads and disposed in said envelope, arcing points extending from said leads into close proximity to one another, and an inert gas filling at a starting pressure of from about ten to fifty millimeters of mercury; comprising applying electric power of such a character to said leads that, first, an arc breaks between said points, because of the initial low pressure of the gas filling, and the lamp runs on a relatively high current at 30 reduced voltage, with the heat of the arc vaporizing the mercury and building up a pressure thereof, second, extinguishing the arc by said pressure of the mercury and, then, operating the filament on full voltage at the desired temperature in the protective atmosphere consisting mainly of the mercury vapor which was developed and maintained by the heat of operation.
